UNITED STATES PATENT OFFICE.

STANLEY D. NICHOLS, OF ROXBURY, VERMONT.

NURSING-BOTTLE.

1,108,778.

Specification of Letters Patent. Patented Aug. 25, 1914.

Application filed April 19, 1913. Serial No. 762,267.

To all whom it may concern:

Be it known that I, STANLEY D. NICHOLS, a citizen of the United States, residing at Roxbury, in the county of Washington and State of Vermont, have invented new and useful Improvements in Nursing-Bottles, of which the following is a specification.

This invention relates to bottles and more particularly to nursing bottles, the object 10 of the invention being to provide a bottle of this character in which the nipple is firmly retained upon the neck.

Frequently the infant pulls the nipple off the bottle and spills all of the milk, thus necessitating refilling of the bottle and reclothing of the child. Several attempts have been made to secure an efficient and sanitary arrangement for securing the nipples in position positively but, to the best of my 20 knowledge, no such construction has yet been placed on the market.

It is, therefore, the object of this invention to avoid the aforesaid difficulties and to provide a positive lock for the nipple.

25 Further objects of the invention will appear as the following description is read in connection with the accompanying drawing which forms a part of this application, and in which:

30 Figure 1 is a sectional view taken through the neck of the bottle and showing one form of the device. Fig. 2 is a similar view showing another form.

Referring more particularly to the drawing, 1 represents an ordinary nursing bottle having a neck 2 which is provided with an annular groove 3 adapted to receive the bead 4 on the lower end of the nipple 5. The lower portion of the neck or that portion 35 joining the body of the bottle is somewhat larger than the outer portion of the neck and is provided with screw threads 6 to receive a locking collar or band 7 which is

threaded thereon and is provided with an annular flange or extension 8 which is adapted to closely fit the nipple and hold the bead in engagement with the groove, the resilience of the nipple of course assisting in this function. Fig. 2 shows the bottle similarly formed but the band or collar 9 is not provided with the extension or flange 8, the collar being long enough to extend up over the bead of the nipple and is normally arranged on the bottle neck and is screwed up over the nipple, whereas in Fig. 1 the band 55 is threaded on the neck after the nipple has been placed in position. It will be noted in these figures that the upper portion of the neck is sufficiently small to permit the removal of the band when it is necessary to clean the bottle.

From the foregoing it will be seen that in all of the structures described the nipple is held firmly upon the neck of the bottle so that it cannot be loosened up or accidentally removed by the infant.

What is claimed is:

In combination, a bottle provided with an annular groove in its neck adapted to receive the bead of a nipple, a nipple having a bead to fit said groove, an enlarged threaded portion on said neck below the groove, and a continuous circular locking band threaded on the neck and adapted to hold said bead within the groove, said band arranged to pass over the nipple when the nipple is applied to the neck, whereby the nipple can be removed without removing the band.

In testimony whereof I affix my signature 30 in presence of two witnesses.

STANLEY D. NICHOLS.
